UNITED STATES PATENT OFFICE.

CHARLES J. ALCAN, OF CHICAGO, ILLINOIS, ASSIGNOR TO RELIANCE METAL SPINNING COMPANY, OF NEW YORK, N. Y., A COPARTNERSHIP COMPRISING SAMUEL SHAPIRO, JOSEPH SHAPIRO, SOLOMON SHAPIRO, DAVE SHAPIRO, AND MORRIS BERMAN.

DESIGN FOR A CANOPY FOR GAS AND ELECTRIC FIXTURES.

49,104.

Specification for Design.

Patented May 30, 1916.

Application filed March 1, 1916. Serial No. 81,555. Term of patent 3½ years.

To all whom it may concern:

Be it known that I, CHARLES J. ALCAN, a citizen of the United States, residing at Chicago, in the county of Cook and State of Illinois, have invented a new, original, and ornamental Design for a Canopy for Gas and Electric Fixtures, of which the following is a specification, reference being had to the accompanying drawing, forming part thereof.

Figure 1 is a side view of a canopy for

gas and electric fixtures, showing my new design. Fig. 2 is a bottom plan view of the structure shown in Fig. 1.

I claim:

The ornamental design for a canopy for gas and electric fixtures, as shown.

CHARLES J. ALCAN.
